UNITED STATES PATENT OFFICE.

ALBERT SCHOENHUT, OF PHILADELPHIA, PENNSYLVANIA.

DESIGN FOR A TRUMPET.

SPECIFICATION forming part of Design No. 21,841, dated September 6, 1892.

Application filed August 13, 1892. Serial No. 443,031. Term of patent 7 years.

To all whom it may concern:

Be it known that I, ALBERT SCHOENHUT, a citizen of the United States, and a resident of Philadelphia, Pennsylvania, have invented a new and original Design for a Trumpet, of which the following is a specification.

My design for a trumpet is fully illustrated in the accompanying drawing, which represents a side view of the trumpet.

- The design relates especially to the enlarged end of the trumpet; and the essential feature of the design consists in forming this portion of the trumpet in simulation of a rooster's head with open beak. -
- 5 A is the body portion of the trumpet, B the

mouthpiece, and D the enlarged end of the trumpet, which, as stated, is formed as a representation of a rooster's head with its beak open.

I claim—

The design for a trumpet, as herein described, and as shown in the accompanying drawing.

In testimony whereof I have signed my name to this specification in the presence of 25 two subscribing witnesses.

ALBERT SCHOENHUT.
